INDICIA-CARD HOLDER

Herbert G. Shaw, Derby, Conn., assignor to Great American Industries, Inc., Meriden, Conn., a corporation of Delaware

Application October 19, 1943, Serial No. 506,914

19 Claims.

(Cl. 40—63)

The present invention relates to improvements in indicia-card holders, e. g., holders for cards or their equivalent bearing personal names or other indicia. The holders of the present invention are specially well-suited for use in conjunction with multiple call-bell systems such as are commonly employed in the vestibules of apartment houses and the like, though the holders of the present invention are obviously useful in other situations where it is desired to hold and protect a card or its equivalent on which is marked a personal name or any other desired indicia.

One of the objects of the present invention is to provide a superior holder for name- or other indicia-cards whereby such cards may be securely mounted in a readily visible manner.

Another object of the present invention is to provide a superior holder for transparent or translucent indicia-cards and in which the indicia on such cards may be rendered readily visible by trans-luminescence.

A further object of the present invention is to provide a superior holder-unit of the character referred to which may be economically produced and which may be conveniently and readily assembled with other similar units.

Still another object of the present invention is to provide a superior indicia-card holder so constructed and arranged that an individual indicia-holder may be readily removed from a mounting panel or the like for effecting a change of indicia-cards, while still insuring that such individual indicia-holder may not be dismounted or otherwise harmfully tampered with by unauthorized persons.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a view in front elevation of a call-box having a front cover-plate or mounting-panel and in which latter is mounted a plurality of indicia-card holders embodying the present invention;

Fig. 2 is a view thereof partly in side elevation and partly in vertical section;

Fig. 3 is a broken view in rear elevation of the mounting-panel detached and showing a plurality of holders mounted therein;

Fig. 4 is a broken vertical sectional view taken on the line 4—4 of Fig. 3 but on a larger scale;

Fig. 5 is a broken horizontal sectional view taken on the line 5—5 of Fig. 3 but on a larger scale;

Fig. 6 is a small-scale view in front elevation of the mounting-panel detached and stripped of card-holding units and associated features;

Fig. 7 is a perspective view of one of the card-holding units;

Fig. 8 is a similar view of one of the retaining-clips;

Fig. 9 is a sectional view of the same general character as Fig. 5 but showing a modified form of mounting-panel;

Fig. 10 is a perspective view of one of the shims, and

Fig. 11 is a perspective view of a modified form of retaining-clip useful in lieu of the retaining-clip shown in the preceding figures.

The particular embodiment of the present invention herein chosen for illustration includes a plurality of corresponding card-holding units or members 15 mounted in a plate-like mounting-panel or -member 16 which latter serves as a removable cover-plate for the otherwise open front of a call-box 17.

The mounting-panel 16 above referred to is removably secured over the open-front face of the call-box 17 in any suitable manner such, for instance, as by four (more or less) screws 18, as indicated in Figs. 1 and 2. In its upper portion, the said mounting-panel 16 is formed with a rectangular opening 19 covered over by a grill 20 behind which may be mounted a telephone transmitter and loud-speaking receiver. In its lower portion, the mounting-panel 16 is formed with three rectangular openings or apertures respectively designated 21, 22 and 23 for purposes as will hereinafter appear.

Mounted in the left-hand opening 21 in the lower portion of the mounting-panel 16 is a vertically-superimposed series of six (more or less) card-holding units 15 before referred to. Simi-

larly, the right-hand opening 23 in the mount-

ing-panel 16 has mounted therein a vertical series of six (more or less) card-holding units or members 15. The central opening 22 lying hor-

izontally intermediate the left and right open-
ings 21 and 23, has exposed therethrough a ver-
tical series of superimposed signal-blocks 24.
The series of signal-blocks 24 mount two vertical
series of push buttons 25 respectively located ad-
jacent each of the respective opposite edges of
the said series of signal-blocks. In a manner

customary in call-boxes each push-button 25 is adapted to close an electric circuit to operate a buzzer or other call-device of a given apartment. The signal-blocks 24 and their push-buttons 25 per se form no essential feature of the present invention but it may be noted that one of the push-buttons 25 is located adjacent the inner edge of each of the card-holding units 15 so as to be identified therewith.

Each of the card-holders 15 preferably corresponds in all details to each other card-holder and is preferably formed of a transparent or translucent material such as cellulose-acetate or any one of the many available synthetics. Each card-holding unit 15 is, in the instance shown, formed at its front with a rim-portion 26 of rectangular frame-like outline and laterally surrounding an oblong front wall 27 which is formed in a plane back of the plane of the front face of the rim-portion 26, as is clearly shown in Figs. 4 and 5.

As shown, each of the card-holding units 15 is of elongated rectangular form in elevation and has integrally projecting from each of the respective opposite ends of its rim-portion 26, one of two corresponding oppositely-extending stop-flanges 28-28. The respective rear faces of the said stop-flanges 28-28 bear against the front face of the mounting-panel 16 on each of the respective opposite sides of the particular one of the openings 21 or 23 in which the given card-holding unit is located.

At each of its top and bottom edges the card-holding unit 15 is formed with one of two parallel retaining-flanges 29-29 extending perpendicularly with respect to the stop-flanges 28-28 and the front wall 27. Adjacent one end of the unit 15 the retaining-flanges 29-29 may be integrally connected together by an end-wall 30 as is especially well shown in Fig. 7. The end of the unit 15 opposite the end-wall 30 is substantially open as shown, but at this location there is formed a pair of shallow card-holding lugs 31-31, functioning in a manner, as will herein-after appear, to hold a card in place in the unit 15.

As before pointed out the card-holding unit or member 15 is preferably molded or otherwise formed from a transparent or translucent material such, for instance, as cellulose-acetate. Preferably, also, the front face of the said unit is rendered opaque by a coating of lacquer or the like, save only the front face of the front wall 27 within the bounds of the rim-portion 26. In this manner light may be transmitted through the localized area of the front wall 27 to permit the ready observation of names or other indicia on an indicia-card 32 located against the back face of the front wall 27 and held in place against edgewise shifting by the retaining-flanges 29-29, end-wall 30 and holding-lugs 31-31.

In the particular instance shown for purposes of illustration, six of the card-holding units 15 are mounted one above the other in each of the openings 21 and 23 of the mounting-panel 16 making a total of 12 units. Preferably and as shown, each card-holding unit has a vertical dimension corresponding to the vertical distance between two adjacent push buttons 25 of the signal-blocks 24 so as to locate the inner edge of a given card-holding unit horizontally in line with one of the push buttons 25.

When a group of card-holding units such as 15 are installed in a given opening such as 21 or 23, one of the horizontal rearwardly-projecting

retaining-flanges 29 of a given unit has its other face substantially in contact with the outer face of one of the retaining-flanges 29 of an adjacent card-holding unit, as is especially well shown in Fig. 4.

Fitting over the juxtaposed retaining-flanges 29-29 of a given pair of adjacent card-holding units 15 is one of a series of retaining-clips or -members each generally designated by the reference character 33.

Each of the retaining-clips 33 above referred to includes a top wall 34, two opposed side-flanges 35-35 extending in parallelism with each other and two resilient stop-fingers 36-36 respectively extending forwardly and outwardly from the respective opposite ends of the top wall 34. Each of the side-flanges 35-35 is formed with two (more or less) anchor-prongs 37-37 cut directly from the material of the given side-flange and each anchor-prong having a pointed end directed inwardly away from the mounting-panel 16 and toward the top wall 34. The lower edge of each of the side-flanges 35-35 is turned outwardly to form an edge-flange 38 and each given edge-flange has its respective opposite ends cut free of the side-flange of which it forms a part, so as to provide two oppositely-extending resilient card-holding fingers 39-39.

Preferably, each retaining-clip 33 is formed of sheet metal and all of its features 34 to 39 inclusive above referred to are integral with the rest of the retaining-clip.

The normal distance between the substantially parallel complementary side-flanges 35-35 of a given retaining-clip is slightly less than the combined thicknesses of two juxtaposed retaining-flanges 29-29 of an adjacent pair of card-holding units. When a retaining-clip 33 is forced forwardly over such a pair of juxtaposed retaining-flanges 29-29, the side-flanges 35-35 will be slightly sprung apart and the retaining-clip will be forced forwardly until the front end of its inclined flexible stop-fingers 36-36 seats against the back face of the mounting-panel 16 as is clearly shown in Fig. 5. When the retaining-clips are mounted as just described, the pair of anchor prongs 37 of each side-flange 35-35 will bite into the material of the adjacent retaining-flange 29 to thus firmly anchor both parts 15 and 33 in place against accidental separation. When a given retaining-clip 33 is fully seated in place as shown in Figs. 4 and 5, the complementary flexible card-holding fingers 39-39 of a given side-flange 35 will press against the rear face of the transparent or translucent indicia card 32 along one longitudinal edge thereof and serve to prevent the same from being displaced rearwardly. Thus the total of four card-holding fingers 39 provided on each of the retaining-clips 33 will serve to aid in retaining in place two indicia cards respectively located in adjoining card-holding units as will be apparent by reference to Fig. 4 in particular.

Instead of employing a retaining-clip or -member such as is shown in Figs. 1 to 9 inclusive, a modified form of retaining-clip may be employed such, for instance, as the retaining-clip or -member 40 illustrated in Fig. 11. The retaining-clip or -member 40 of Fig. 11 corresponds generally to the retaining-clip of the preceding figures and similar parts bear similar reference numerals plus the reference character *a*. In this retaining-clip, however, the edge-flanges 38*a* do not have integral card-holding fingers at their respective opposite ends but instead are provided

adjacent their central portions with two longitudinally-spaced-apart notches 41-41. Inserted into each of the complementary pair of notches 41-41 in a given edge-flange 38a is a bowed sheet-metal spring 42 having at each of its respective opposite ends one of two card-holding fingers 43 capable of serving to retain an indicia card in place in lieu of the card-holding fingers 39-39 previously described.

In fitting a retaining-clip such as either 33 or 40 over the outer retaining-flange 29 of a card-holding unit which is located either at the top or bottom of a given opening such as 21 or 23, it is desirable to employ a shim such as the shim 44 illustrated in Figs. 4 and 10 so that the chosen retaining-clip will have the space between its complementary side-flanges 35-35 or 35a-35a adequately filled to a degree substantially corresponding to the combined thicknesses of two anchoring-flanges 29.

If desired and as shown in Fig. 9 the mounting-panel 16a may be substituted for the mounting-panel 16. The mounting-panel 16a may have one or more openings such as 21a therein and around such opening the metal or other material of the mounting-panel is set inwardly to provide a pocket 45 substantially corresponding in depth to the thickness from front to rear of the stop-flanges 28-28 of a card-holding unit 15. In this manner, an unauthorized person intending to pry one of the card-holding units forwardly will be handicapped in endeavoring to insert a pen-knife or other tool to obtain a leverage.

Incandescent electric bulbs such as the bulb 46 shown in Fig. 2 may be mounted back of the mounting-member 16 or 16a so as to throw light forwardly through the transparent or partially transparent (translucent) front wall 21 of the card-holding unit 15 after first passing through the transparent or semi-transparent (translucent) indicia card 32.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. An indicia-card-holding structure, including in combination: a mounting-member formed with a holder-receiving aperture; a frame-like card-holding unit installed in the aperture in the said mounting-member and having two stop-flanges respectively projecting in opposite directions therefrom adjacent the outer face of the unit, the said stop-flanges having inner faces seating against the outer face of the said mounting-member to limit the rearward displacement of the unit relative to the said mounting-member, the said card-holding unit also having two anchoring-flanges extending rearwardly beyond the rear face of the said mounting-member; and anchoring-means engaging the two rearwardly-extending anchoring-flanges of the said card-holding unit and a rearwardly-facing portion of the said mounting-member to hold the said unit against forward displacement with respect to the said mounting-member.

2. An indicia-card-holding structure as set forth in claim 1 and in which the said anchoring-means is provided with an anchor-prong posi-

tioned to bite into the anchoring-flange of the card-holding unit with which the said anchoring-means is engaged.

3. An indicia-card-holding structure, including in combination: a mounting-member formed with a holder-receiving aperture; a frame-like card-holding unit installed in the aperture in the said mounting-member and having two stop-flanges respectively projecting in opposite directions therefrom adjacent the outer face of the unit, the said stop-flanges having inner faces seating against the outer face of the said mounting-member to limit the rearward displacement of the unit relative to the said mounting-member, the said card-holding unit also having two anchoring-flanges extending rearwardly beyond the rear face of the said mounting-member; and anchoring-means engaging the two rearwardly-extending anchoring-flanges of the said card-holding unit and a rearwardly-facing portion of the said mounting-member to hold the said unit against forward displacement with respect to the said mounting-member, the said anchoring-means having card-retaining means thereon extending into position between the anchoring-flanges of the said card-holding unit to retain an indicia-card against a rear face of the said unit.

4. An indicia-card-holding structure as defined in claim 3 and in which the card-retaining means of the said anchoring-means is in the form of a resilient finger.

5. An indicia-card-holding structure as defined in claim 3 and in which the card-retaining means of the said anchoring-means is in the form of a resilient finger and in which the said anchoring-means is also provided adjacent its said card-retaining means with an anchoring-prong positioned to bite into the anchoring-flange of the card-holding unit with which the anchoring means is engaged.

6. An indicia-card-holding structure, including in combination: a mounting-member formed with a holder-receiving aperture; a frame-like card-holding unit installed in the aperture in the said mounting-member and having two stop-flanges respectively projecting in opposite directions therefrom adjacent the outer face of the unit, the said stop-flanges having inner faces seating against the outer face of the said mounting-member to limit the rearward displacement of the unit relative to the said mounting-member, the said card-holding unit also having two rearwardly-extending anchoring-flanges located on the edges thereof intermediate the two said stop-flanges and projecting rearwardly beyond the rear face of the said mounting-member; and anchoring-means engaging the two rearwardly-extending anchoring-flanges of the said card-holding unit and a rearwardly-facing portion of the said mounting-member to hold the said unit against forward displacement with respect to the said mounting-member.

7. An indicia-card-holding structure, including in combination: a mounting-member formed with a holder-receiving aperture; a plurality of juxtaposed frame-like card-holding units installed in the aperture in the said mounting-member and each having two stop-flanges respectively projecting in opposite directions therefrom adjacent the outer face of the unit, the said stop-flanges having inner faces seating against the outer face of the said mounting-member to limit the rearward displacement of the unit of which it forms a part relative to the said mounting-member, each of the said card-holding units also having

two anchoring-flanges extending rearwardly beyond the rear face of the said mounting-member, one of the anchoring-flanges of one card-holding unit being located adjacent the similar anchoring-flange of an adjacent card-holding unit; and an anchoring-member engaging the respective adjacent anchoring-flanges of a pair of juxtaposed card-holding units, the said anchoring-member also having a portion engaging a rearwardly-facing portion of the said mounting-member to hold the said anchoring-member against forward displacement with respect to the said mounting-member.

8. An indicia-card-holding structure as set forth in claim 7 and in which the anchoring-member is provided with at least two anchor-prongs respectively positioned to bite into the anchoring-flange of one of the two card-holding units with which the said anchoring-member is engaged.

9. An indicia-card-holding structure, including in combination: a mounting-member formed with a holder-receiving aperture; a plurality of juxtaposed frame-like card-holding units installed in the aperture in the said mounting-member and each having two stop-flanges respectively projecting in opposite directions therefrom adjacent the outer face of the unit, the said stop-flanges having inner faces seating against the outer face of the said mounting-member to limit the rearward displacement of the unit of which it forms a part relative to the said mounting-member, each of the said card-holding units also having two anchoring-flanges extending rearwardly beyond the rear face of the said mounting-member, one of the anchoring-flanges of one card-holding unit being located adjacent the similar anchoring-flange of an adjacent card-holding unit; and an anchoring-member engaging the respective adjacent anchoring-flanges of a pair of juxtaposed card-holding units, the said anchoring-member also having a portion engaging a rearwardly-facing portion of the said mounting-member to hold the said anchoring-member against forward displacement with respect to the said mounting-member, the said anchoring-member having two card-retaining means thereon respectively extending into position between the anchoring-flanges of a given one of the said card-holding units to retain an indicia card against the respective rear face of the said units.

10. An indicia-card-holding structure as set forth in claim 9 and in which each of the card-retaining means of the said anchoring-member is in the form of a resilient finger.

11. An indicia-card-holding structure as set forth in claim 9 and in which each of the card-retaining means of the said anchoring-member is in the form of a resilient finger and in which the said anchoring-member is also provided adjacent each of its said card-retaining means with an anchoring-prong positioned to bite into one of the anchoring-flanges of the adjacent card-holding unit.

12. An indicia-card-holding structure, including in combination: a mounting-member formed with a holder-receiving aperture; a plurality of juxtaposed frame-like card-holding units installed in the aperture in the said mounting-member and each having two stop-flanges respectively projecting in opposite directions therefrom adjacent the outer face of the unit, the said stop-flanges having inner faces seating against the outer face of the said mounting-member to limit

the rearward displacement of the unit of which it forms a part relative to the said mounting-member, each of the said card-holding units also having two anchoring-flanges located on the edges thereof intermediate the two said stop-flanges and extending rearwardly beyond the rear face of the said mounting-member, one of the anchoring-flanges of one card-holding unit being located adjacent the similar anchoring-flange of an adjacent card-holding unit; and an anchoring-member engaging the respective adjacent anchoring-flanges of a pair of juxtaposed card-holding units, the said anchoring-member having a portion engaging a rearwardly-facing portion of the said mounting-member to hold the said anchoring-member against forward displacement with respect to the said mounting-member.

13. An indicia-card-holding structure including in combination: a mounting-member formed with a holder-receiving aperture; a frame-like card-holding unit installed in the aperture in the said mounting-member and having stop-means thereon seated against the outer face of the said mounting-member to limit the rearward displacement of the unit relative to the said mounting-member, the said card-holding unit also having an anchoring-flange extending rearwardly beyond the rear face of the said mounting-member; and anchoring-means engaging the rearwardly-extending anchoring-flange of the said card-holding unit and a rearwardly-facing portion of the said mounting-member to hold the said unit against forward displacement with respect to the said mounting-member.

14. An indicia-card-holding structure, including in combination: a mounting-member formed with a holder-receiving aperture; a plurality of juxtaposed frame-like card-holding units installed in the aperture in the said mounting-member and each having stop-means thereon seating against the outer face of the said mounting-member to limit the rearward displacement of the unit of which it forms a part relative to the said mounting-member, each of the said card-holding units also having two anchoring-flanges extending rearwardly beyond the rear face of the said mounting-member, one of the anchoring-flanges of one card-holding unit being located adjacent the similar anchoring-flange of an adjacent card-holding unit; and an anchoring-clip of substantially U-shaped form in cross-section and having two substantially parallel side-flanges embracing between them the respective adjacent anchoring-flanges of a pair of juxtaposed card-holding units, the said anchoring-clip also having a portion engaging a rearwardly-facing portion of the said mounting-member to hold the said anchoring-clip against forward displacement with respect to the said mounting-member.

15. An indicia-card-holding structure, including in combination: a mounting-member formed with a holder-receiving aperture; a plurality of juxtaposed frame-like card-holding units installed in the aperture in the said mounting-member and each having stop-means thereon seating against the outer face of the said mounting-member to limit the rearward displacement of the unit of which it forms a part relative to the said mounting-member, each of the said card-holding units also having two anchoring-flanges extending rearwardly beyond the rear face of the said mounting-member, one of the anchoring-flanges of one card-holding unit being located adjacent

the similar anchoring-flange of an adjacent card-holding unit; and an anchoring-clip of substantially U-shaped form in cross-section and having two substantially-parallel side-flanges embracing between them the respective adjacent anchoring-flanges of a pair of juxtaposed card-holding units, the said anchoring-clip also having at each of its respective opposite ends one of two complementary stop-fingers engaging a rearwardly-facing portion of the said mounting-member.

16. An anchoring-clip for indicia-card-holding structures, including in combination: a body-portion of substantially U-shaped form in cross-section having two substantially-parallel side-flanges constructed and arranged to embrace between them portions of a pair of juxtaposed card-holding units, the said anchoring-clip being provided at each of its respective opposite ends with stop-fingers extending in the same general direction as the side-flanges of the anchoring-clip.

17. A frame-like indicia-card-holding unit of rectangular form in elevation and having two stop-flanges respectively projecting in opposite directions therefrom adjacent the forward face of the unit, and a pair of laterally-spaced-apart anchoring-flanges respectively located adjacent the side-edges of the unit and projecting backwardly away from the front face thereof to provide between them a card-receiving cavity and an integral front wall having light-transmitting properties to permit an indicia-card mounted against the rear face of the said front wall to be observed by light passing forwardly between the two said stop-flanges.

18. An indicia-card-holding structure including in combination: a call-box structure having a removable front formed with a relatively-large holder-receiving aperture; a series of physically-distinct card-holding units located in the holder-receiving aperture in the removable front of the call-box in juxtaposed relationship; and retaining-means engaging with both the removable front of the call-box structure and the said card-holding unit to retain the latter in place in the former, the said retaining-means being constructed and arranged to be releasable only from the rear face of the removable front of the said call-box structure.
19. An indicia-card-holding structure, including in combination: a mounting-member formed with a holder-receiving aperture; a frame-like card-holding unit installed in the aperture in the said mounting-member and having two stop-flanges respectively projecting in opposite directions therefrom adjacent the outer face of the unit, the said stop-flanges having inner faces seating against the outer face of the said mounting-member to limit the rearward displacement of the unit relative to the said mounting-member, the said card-holding unit having means thereon projecting into the aperture in the said mounting-member; and anchoring-means engaging both the mounting-member and the card-holding unit and constructed and arranged to restrain the said unit against forward displacement.

HERBERT G. SHAW.
